RACK FOR STEREO TAPE CARTRIDGES

Robert Adell, Birmingham, Mich., assignor to Adell International, Inc., Detroit, Mich., a corporation of Michigan

Filed Jan. 3, 1967, Ser. No. 5,280

Term of patent 14 years

(Cl. D33—3)

FIG. 1 is a front elevational view of a rack for stereo tape cartridges showing my new design;

FIG. 2 is a top plan view;

FIG. 3 is an end elevational view;

FIG. 4 is a bottom view;

FIG. 5 is a perspective view taken from the left side of FIG. 1.

The characteristic features of my design reside in the specific arrangement and spaced relation of the shelf supporting members of the claimed rack, as best illustrated in FIGS. 1 and 5 on the drawing.

I claim:

The ornamental design for a rack for stereo tape cartridges, as shown and described.
